UNITED STATES PATENT OFFICE.

JESSE M. PERICLE, OF HUTCHINSON, MINNESOTA.

SNAP HOOK.

Application filed June 20, 1924. Serial No. 721,294.

To all whom it may concern:

Be it known that I, JESSE M. PERICLE, a citizen of the United States, residing at Hutchinson, in the county of McLeod and 5 State of Minnesota, have invented certain new and useful Improvements in Snap Hooks, of which the following is a specification.

This invention aims to provide a snap hook of great strength primarily intended 10 for use by farmers for tethering cattle, particularly strong bulls, for which reason this hook may properly be known as a "bull snap."

15 One embodiment of the invention is illustrated in the accompanying drawing, in which

Figure 1 shows a side elevation and partial section of the device, and

20 Figure 2 is a section on the line 2—2 of Figure 1.

In the drawing, the reference numeral 10 represents one of the side bars and the reference numeral 11 the other side bar of the 25 snap hook. These side bars are arranged in spaced parallel relation and are connected at one end by an arm 12. The side bar 11 is shorter than the side bar 10, the latter terminating in a hook 13 which is bent back in 30 the plane of the bars. At the end of the hook 13 is formed an enlarged head provided with a socket 14 facing the end of said other side bar 11.

A brace 15 firmly connects the end of the 35 side bar 11 with the side bar 10. A longitudinal chamber 16 is formed in the side bar 11 adapted to receive and form a guide for a sliding bolt or plunger 17. The outer end of the sliding bolt normally projects beyond 40 the end of the side bar 11 and engages in the socket 14 to be supported thereby. A coiled compression spring 18 is inserted in the chamber 16 back of the plunger or sliding bolt 17 and tends to push the latter into 45 engagement with the socket 14. The space 19 between the ends of the hook and the side bar 11 is sufficiently wide, when open, to permit of the insertion of a stout rope or the link of a chain. The reference numeral 20 50 represents an eyelet or ring which has swiveled connection with the transverse arm 12.

The wall of the chamber 16 facing the side bar 10 is provided with a longitudinal slot 21, the rear end of which terminates in 55 a notch 22. Through this slot projects a finger piece 23 which is secured to the slid-

ing bolt and by means of which said bolt may be retracted to open the hook. If it is desired to leave the space 19 open, the finger piece, after having been drawn all the way back, is swung into engagement with the notch 22. This will retain the bolt in retracted position against the action of the spring 18. A slight side pressure on the finger piece will release the bolt 17 which will 60 then be pushed forward by the spring 18.

Having thus described the invention, I claim:

1. A snap hook comprising a pair of parallel side bars, an arm forming a rigid connection between the said bars at one end thereof, a brace spaced from the arm and forming a rigid connection between the side bars near the other end thereof, a ring swiveled on the arm between the side bars and 70 projecting rearwardly from said arm, one of the side bars being provided with an overhanging hook terminating in an enlarged head, a space being formed between the end of the hook and the end of the other side 75 bar, and means adapted to close said space, said means including a spring actuated sliding bolt arranged on the other side bar, a socket being provided in the enlarged head 80 of the hook adapted to receive the end of 85 the bolt.

2. A snap hook comprising a pair of parallel side bars one of which is hollow to provide a chamber, an arm forming a rigid connection between the side bars at one end 90 thereof, a brace between the side bars, one of the side bars being provided with an integral overhanging hook terminating in an enlarged head, a space being formed between the end of the hook and the end of the hollow side bar, means adapted to close said space, said means including a sliding bolt disposed within the chamber, a socket being formed in the enlarged head of the hook 95 adapted to receive the end of the bolt, a spring arranged in said chamber tending to hold the terminal of the bolt within the socket, and a finger-piece on the bolt extending through a slot provided in the hollow side bar, said finger-piece normally pointing 100 in the direction of the hooked side bar and being normally housed between said side bars.

3. A snap hook comprising spaced parallel side bars one of which is hollow to form 110 a chamber, an arm forming a rigid connection between the side bars at one end there-

of, a brace spaced from the arm and forming a rigid connection between the side bars near the other end thereof, the other side bar being provided with an integral overhanging hook terminating in an enlarged head, a space being formed between the end of the hook and the hollow side bar, a swivel eye carried by and extending rearwardly from the connecting arm between said side bars, 10 means adapted to close said space, said means including a sliding bolt arranged within the chamber of the hollow bar, there

being a socket formed in the enlarged head of the hook adapted to receive the end of the bolt, a spring seated in said chamber tending to hold the end of the bolt in said socket, and a finger-piece on the bolt extending through a slot in the hollow bar, said finger-piece normally extending in the direction of the hooked side bar and said slot having a 20 notch adapted to receive the finger-piece to hold the bolt in retracted position.

In testimony whereof I affix my signature.
JESSE M. PERICLE. [L. S.]
